COMMUNICATION SYSTEM

Austin R. Noll, New York, N. Y., assignor to International Business Machines Corporation, New York, N. Y., a corporation of New York

Application October 23, 1935, Serial No. 46,278

11 Claims. (Cl. 178—68)

This invention relates to communication systems and more particularly to selecting systems of the non-synchronous type.

The principle of operation of the system employed in the present invention instead of depending on the synchronous operation of the transmitting and receiving units operates on the basis of the transmission of signals of predetermined current values to which the receiving unit 5 will give a definite and different response to each signal. A system of this type is fully disclosed and described in a copending application, Serial No. 737,013, filed July 26, 1934.

The present invention is in the form of an improvement of the system described in the aforesaid application. Briefly and broadly, the system in said application comprises a transmitting unit to initiate character signals consisting of code combinations of impulses having differential 10 current values and polarity. The receiving unit includes relay devices sensitive to said impulse characteristics to control the selection of different circuits, for example, a galvanometer relay of the D'Arsonval type may be used to respond to the different current values employed and the 15 polarity of the impulses, so that the relay brush or armature is positioned to engage one of a plurality of contacts in accordance with the characteristics of the character signal. In addition thereto, another relay device may be used to be responsive only to the number of impulses included in the code combinations, in turn, controlling a device such as a relay to be operated 20 step by step such as the well known type of stepping relay.

A plurality of circuits are associated with the galvanometer relay contacts and with the contacts of the stepping relay and are arranged so that upon the respective positioning of the galvanometer relay and the stepping relay, a single 25 circuit corresponding to the character signal is selected to be energized effecting registration of the selected character.

It is an object of the present invention to provide for a simplified selecting system which is capable of a faster rate of operation than heretofore for similar type systems. The object is achieved by including the following features: by elimination of the said galvanometer relay and 30 said stepping relay and substituting therefor simple individual relays and associated control circuits.

Various other objects and advantages of the invention will be obvious from the following particular description of one form of mechanism em-

bodying the invention or from an inspection of the accompanying drawings; and the invention also constitutes certain new and useful features of construction and combination of parts hereinafter set forth and claimed.

In the drawings:

Fig. 1 is a schematic diagram showing one form of the connections of the impulse transmitter.

Fig. 2 is a preferred form of the code used in conjunction with the present invention.

Fig. 3 is a schematic diagram showing one form of circuit arrangement of the receiving system.

Referring now to Fig. 1, a plurality of pulse wheels or disks 14 are shown with a combination 15 of conducting segments 16 thereon. The arrangement and number of conducting segments for each disk corresponds to the code shown in Fig. 2, for example, the character "P", the code of which is current value 4, positive polarity and 20 four impulses, namely, three short impulses and one long impulse. Therefore, on the disk 14 for the said character, four conducting segments 16 are disposed thereon so that the three short pulses of current are conducted before the long 25 segment engages the contacts 17 to transmit the long impulse of its corresponding current value.

It is to be noted that for the characters represented by a plurality of impulses, the last impulse is always a long impulse, the significance of which 30 will be understood as the description progresses. Each disk therefore has disposed thereupon the number of segments to correspond to the number of impulses in its particular code. It is sufficient to mention that upon depression of a 35 character key of a typewriter (not shown) its corresponding disk 14 is released to complete one revolution, thereby conducting the proper increment of current value, polarity and the number of impulses representing the character, to the 40 connected line network. A further description of the transmitting system may be had by referring to the said prior application in which the transmitting typewriter and mechanism for releasing the pulse is shown and completely described. Since this mechanism forms no part 45 of the invention, it is deemed unnecessary to repeat such description.

With reference now to Fig. 3, the combinational code of impulses representing the character signals are impressed upon a line associated with relays 25 and 26. Relay 25 may be a polar relay device and is responsive to the current polarity of the impulses to position the armature 27 to engage contact 28 or contact 29 when the 55

impulses are of positive or negative polarity respectively.

The positioning of armature 27 is effective to connect the line upon which the signal impulses are impressed to either the group of relays 21 to 24 inclusive or the group of relays 21-B to 24-B inclusive. The description of operation will be limited to the group of relays 21 to 24 and the method of effecting a circuit selection by said relays, since it will be obvious as the description progresses that the group of relays 21-B to 24-B are operated in exactly in the same manner as the group to be described presently. The said groups of relays are shown to comprise conventional energizing windings or coils designated 21-A, 22-A, etc. and holding windings or coils designated 21-C, 22-C, etc. The energizing coils are connected in a parallel group arrangement and terminate at the contacts 28 and 29 of the polar relay 25. Relay 21 is adjusted to be sensitive and responsive to the first current value, relay 22 responsive to the second current value, relay 23 responsive to the third current value and relay 24 responsive to the fourth current value.

It is obvious that upon the reception of a signal pulse of a particular current value, the relay corresponding to that current value will be operated and in addition thereto all the relays adjusted to be responsive to current values less than the said particular current value.

However, only the holding coil of the relay responsive and corresponding to the particular current value will be energized to maintain the selected relay in an operated position. This is effected by the normally closed contacts C-1 and the normally open contacts C-3 of the relays.

For example, assume that the character signal for "P" is impressed upon the line and by reference to Fig. 2 it is seen that the signal comprises four impulses of positive polarity and the fourth current value. Relay 25 is energized to position the armature 27 to engage contact 28 and thereby connects the line by conductor 35 through the normally closed contacts 36, contact 28 and common conductor 38 to the energizing coils of the group of relays 21 to 24. Due to the current value impressed thereupon, relays 21, 22, 23 and 24 are operated momentarily, however, upon operation of the said relays, the normally closed contacts C-1 associated therewith (with the exception of relay 21) are opened thereby preventing battery 38 to energize any of the holding coils 21-C, 22-C, 23-C and 24-C excepting coil 24-C as follows: from grounded battery 38, normally closed contacts 39, conductor 40, coil 24-C, contact C-3 (now closed) associated with relay 24, to ground 41. Contacts C-3 associated with relays 21 to 24 are normally open and prevent any possible energization of the holding coils 21-C to 24-C unless the associated relay is operated. The C-2 contacts associated with the relays 21 to 24 when closed due to the operation of any one of the said relays connect grounded battery 42 by common conductors 43 and 44 to winding of relay 45, operating the said relay and opening the normally closed contacts 36 associated therewith.

This prevents further energization of the energizing coils of the relays 21 to 24 by the particular character impulses impressed on the line during the continued transmission of the character signal pulses, in this manner preventing any

possible chattering of the contacts of the relays 21 to 24.

Connected to the C-4 contacts associated with relays 21 to 24 are the group control relays 31 to 34 respectively. The common conductor 46 connected to the C-4 contacts connects grounded battery 42 to the group control relays when contact 47 is closed. The operation of the said contact 47 is controlled by relay 48 which is connected to the line upon which the character pulses are impressed; the said relay is adjusted to be responsive only to the long impulses of the code which as shown in Fig. 2 are the last impulses transmitted. Operation of relay 48 permits grounded battery to operate one of the relays 31 to 34 through the closed C-4 contact associated with the particular relay of relay groups 21 to 24.

It is seen therefore from the description just set forth, that upon and during the transmission of the character pulses for character "P", relay 24 is energized and a locking circuit is established to maintain the relay in an operated condition until the circuit selection is completed, thereby permitting relay 34, connected to the associated C-4 contact, to be connected in a circuit, which, when the last impulse is received is energized due to the operation of relay 48, and thereby energizing and operating the relay 34 causing the contacts a, b, c, d, associated therewith to be closed. In this manner a predetermined number of circuits, namely four, are selected from a plurality of circuits.

It will now be shown how a further selection of a single circuit is effected from the said predetermined number of circuits.

Relay 26, as mentioned hereinbefore, is associated with the line and is responsive only to the number of character signal impulses included in the combinational code. Operation of relay 26 permits grounded battery 38 to operate relay 50 causing contact 51 to be closed. It is to be noted that for each impulse impressed upon the line relays 26 and 50 are operated and establish momentarily a circuit through the make before break contacts associated with relay 50. Assume now that the signal impulses for character "P" are impressed on the line, namely, three short impulses and one long impulse, of course, it is understood that the polarity and current value of the pulses do not affect this part of the selecting circuit.

Upon reception of the first impulse relays 26 and 50 are operated to provide momentarily a circuit as follows: grounded battery 38, normally closed contacts 39, common conductor 52, winding of relay 53, the normally closed contact associated therewith, contact 51 and the normally closed contact associated with relay 50, contact 54 to ground. This circuit is established momentarily due to the make and break contacts associated with relay 50, however, the said circuit established for an interval of a second permits relay 53 to be operated and locked up through the contact 55 associated therewith.

Contacts 56 and 57 are also operated, contact 56 establishing a circuit to the winding of relay 58 (it is apparent, however, that relay 58 at this time cannot be operated, since the normally closed contact associated with relay 50 is now open) and contact 57 connecting ground 59 to the circuits associated with the common conductor 60 through common conductor 61, normally closed contact 62 and contact 57 now closed. It is noted, however, that a selection of 75

a circuit from the predetermined circuits selected by relay 34 is not affected by the operation of relay 53 and the connection of ground 59 to the circuit 60.

5 Upon reception of the second impulse relays 26 and 50 are operated again establishing a circuit momentarily from grounded battery 38 through normally closed contacts 39, common conductor 52, winding of relay 58, the normally closed contact associated therewith, contacts 56 and 51, now closed, the normally closed contact associated with relay 50 and contacts 54 now closed, to ground. Relay 58 is operated and locked up through the associated contact 63; 10 ground 59 is disconnected from the common conductor 60 by virtue of the normally closed contact 62 being opened upon operation of relay 58 and the said ground is now connected through normally closed contact 64 and contact 65 now closed to the common conductor 66 and the circuits associated therewith. Again, it is apparent that a selection of a circuit from the said predetermined circuits selected by relay 34 is not effected by operation of relay 58 and the connection of ground 59 to the circuit 66.

15 Closure of contact 61 establishes a circuit to winding of relay 68, however, the said relay is not affected until the third operation of relays 26 and 50 which occurs upon the reception of the third impulse and thereby establishing the following circuit momentarily: from grounded battery 38 through normally closed contacts 39 to common conductor 52, winding of relay 68, normally closed contacts associated therewith, contacts 67, 56, and 51 now closed, normally closed contact associated with relay 50 and contact 54 now closed, to ground. Relay 68 is now operated and locked up through the contacts 69 now closed, to ground 59. Said ground is now disconnected from the common conductor 66 due to the contact 64 now opened, and transferred to common conductor 70 through contact 71 now closed, and normally closed contact 72. However, a selection of a circuit from the said predetermined circuits selected by relay 34 is not affected by the connection of the said ground to the common conductor 70.

20 Closure of contact 73 establishes a circuit to winding of relay 74, but it is understood that the said relay is not operated until the reception of the fourth impulse whereupon relays 26 and 50 are operated to establish the following circuit: From grounded battery 38, normally closed contacts 39, common conductor 52, winding of relay 74, the normally closed contact associated therewith and contacts 73, 67, 56 and 51 now closed, normally closed contacts associated with relay 50 and contacts 54 now closed to ground. Relay 74 is operated and locked up through the contact 75 now closed. Ground 59 is transferred from common conductor 70 to common conductor 76, due to the contact 72 being opened and contact 77 being closed due to the operation of relay 74.

25 It is seen now that grounded battery 42 is connected through the common conductor 18, contact d of relay 34, now closed, conductor 19, the "P" solenoid 80, conductor 81, common conductor 76, contacts 77 now closed, to ground 59, energizing the said solenoid 80. Referring to the drawings, it is seen that a solenoid 80 is included in each one of the circuits associated with the a to d contacts of the group control relays 31 to 34; the said solenoids may be associated with 30 a suitable recording or control unit, for ex-

ample, such as a punch or typewriter and may be connected so that upon energization the key bars of the particular registering or recording unit are depressed accordingly to effect registration of the character. Further description of a suitable recorder is deemed unnecessary because a complete disclosure thereof may be had by referring to the said aforementioned application.

35 Similarly, in a manner just described, it is possible to select any of the other solenoid circuits in accordance with the reception of corresponding character signal impulses. Further description of the operating circuits is deemed unnecessary since it is obvious that the selection of any circuit may be effected in a similar manner as explained hereinabove.

40 Upon depression or operation of the key bars of a recording unit, common contacts 39 are adapted to be operated and opened. Specific mechanism for this provision is not shown since it is old and well known in the art; one method which has been used heretofore is to provide a common bar beneath the key bars of the typewriter and arranged so that the depression of the character key bars lowers the common bar which in turn causes the common contacts to be opened.

45 It is apparent from the description set forth hereinabove that upon operation of the contacts 39 all the condition and locked up relays 30 are restored to normal condition due to disconnecting grounded battery 38 from the circuits established and described. Therefore, the relays 53, 58, 68 and 74 operated and locked up successively are restored to normal condition, due to 35 the opening of the said holding circuits, similarly relays 24, 34 and 45 are returned to normal due to opening the respective energized circuits described.

50 It is evident from the description just set forth that upon operation of the recording unit the conditioned control circuits for the relay selecting circuits just described are all restored to the normal condition as shown in the drawings and in a condition to continue subsequent selection of character circuits in accordance with the character signals. From the description set forth regarding the successive selective relay circuits, it is obvious that if the character code combination includes a number of impulses less than four impulses, the conditioning and operation of the circuits are similar to the operations just outlined and that irrespective of the number of impulses transmitted for the character signal, operation of the recording unit restores the conditioned circuits and relays to normal similarly as described herein.

55 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

60 What is claimed is:

65 1. In a communication system comprising a plurality of circuits corresponding to predetermined signals, means for transmitting signals consisting of code combinations of impulses of different current values and polarity, means comprising individual relay devices responsive to said current values and polarity of the impulses and 70

75

means responsive to the different number of impulses included in said code to select circuits corresponding to the transmitted signals from the said plurality of circuits.

- 5 2. In a communication system comprising a plurality of circuits corresponding to predetermined signals, means for transmitting signals consisting of code combinations of impulses of different current strength and polarity, means 10 comprising individual relay devices responsive to said current strength and polarity and means simultaneously responsive to the different number of impulses included in said code to select circuits corresponding to the transmitted signals 15 from the said plurality of circuits, means to energize the said selected circuits, and means to determine the timed interval the said circuits are permitted to remain energized.
3. In a communication system comprising a 20 plurality of circuits corresponding to predetermined signals, means for transmitting signals consisting of code combinations of impulses of different current strengths and polarity, means comprising individual relay devices responsive to 25 said current strengths and polarity and means responsive to the different number of impulses included in said code to select from the plurality of circuits those which correspond to the transmitted signals, means to energize the said selected circuits, and recording means operated by 30 said energized circuits.
4. The invention set forth in claim 3 in which means are provided to deenergize the selected circuits upon operation of said recording means.
35 5. In a selective system, means for transmitting combinations of impulses having different current values and polarity, a plurality of circuits, means comprising individual relay devices responsive to said impulse characteristics and 40 means responsive to the successive and varying number of impulses of the said combinations to select a circuit from the said plurality of circuits.
6. The invention set forth in claim 5 in which means are provided to prevent more than one

of said individual relay devices to be effective in said selection in response to the impulses of predetermined characteristics.

7. In a selective system, means for transmitting code combinations of impulses of predetermined and different current values and polarity, a plurality of circuits, means comprising individual relay devices sensitive and responsive to the particular current value transmitted and means responsive to the polarity and the different 10 number of impulses in the code to select a circuit from said circuits, a number of said relay devices sensitive to current values less than the said particular current value operated by the said particular current value, and means for rendering all the said devices inoperative except the one which is representative of the said particular current value.

8. In a selective system, means for transmitting combinations of impulses having different 20 current values and polarity, a plurality of circuits, means comprising individual relay devices responsive to said impulse characteristics and means comprising a train of individual relay devices responsive to the successive and varying 25 number of impulses of the said combination to select a circuit from the said plurality of circuits.

9. The invention set forth in claim 8 in which means are provided to energize the said selected circuit upon reception of the last impulse of said 30 combination.

10. The invention set forth in claim 8 in which an impulse translating relay device responsive to the number of said impulses is provided to operate the said train of individual relay devices successively by successive operation of said impulse translating device.

11. The invention set forth in claim 8 in which means are provided so that the operation of one of said relay devices of said train establishes a 40 circuit thereby so that the next one of said relays may be operated by the said successive impulses.

AUSTIN R. NOLL.
